O. S. HALL.
SECTIONAL CONCRETE CULVERT.
APPLICATION FILED APR. 14, 1914.

1,130,508.

Patented Mar. 2, 1915.

UNITED STATES PATENT OFFICE.

OWEN S. HALL, OF RED LODGE, MONTANA.

SECTIONAL CONCRETE CULVERT.

1,130,508.

Specification of Letters Patent. Patented Mar. 2, 1915.

Application filed April 14, 1914. Serial No. 831,769.

To all whom it may concern:

Be it known that I, OWEN S. HALL, a citizen of the United States, residing at Red Lodge, in the county of Carbon, State of Montana, have invented certain new and useful Improvements in Sectional Concrete Culverts; and I do hereby declare the following to be a full, clear, and exact description of the invention, such as will enable others skilled in the art to which it appertains to make and use the same.

This invention relates to sectional concrete culverts.

The object of the invention resides in an improved construction of sectional culvert adapted for use beneath the road beds and wherein the sections will be positively held against longitudinal displacement with respect to each other.

A further object of the invention resides in the provision of a sectional culvert which can be easily and quickly assembled and in which the sections can be manufactured at a comparatively small cost.

With the above and other objects in view the invention consists in the details of construction and in the arrangement and combination of parts to be hereinafter more fully described and particularly pointed out in the appended claims.

In describing the invention in detail reference will be had to the accompanying drawings wherein like characters of reference denote corresponding parts in the several views, and in which—

Figure 1 is a side elevation of a culvert constructed in accordance with the invention; Fig. 2, a longitudinal section of what is shown in Fig. 1; Fig. 3, a perspective view looking at one end of one of the intermediate sections of the culvert; Fig. 4, a perspective view looking at the other end of an intermediate section of the culvert; Fig. 5, a perspective view of one of the terminal sections of the culvert, and Fig. 6, a perspective view of the other terminal section of the culvert.

Referring to the drawings the improved culvert is indicated generally at A and is shown as comprising a plurality of intermediate sections 10 sufficient in number to form a culvert of the desired length, and terminal sections 11 and 12.

Each of the intermediate sections 10 includes a flat base 13 and an arched top 14. Each section 10 is provided at one end with

an extension 15 disposed at the top of the section and having its terminal portions inclined downwardly from the inner end of said extension as at 16. Each section 10 is further provided at its other end with an extension 17 disposed at the bottom of the section and having its terminal portions inclined upwardly from the inner end of the extension as at 18. In assembling the intermediate sections the terminal portions 16 of the extension 15 of one section are engaged with the terminal portions 18 of the extension 17 of the next section and in this manner the sections 10 are interlocked with each other so as to be incapable of relative longitudinal movement.

The terminal section 11 includes a flat base portion 19 and a top portion 20, said terminal section being of greater height than the intermediate sections 10 to form a wheel guard 21 and being provided with a bore 22 corresponding to the bore of the sections 10. The section 11 is provided on its inner end with an extension 23, said extension being disposed at the bottom of the section and having its terminal portions inclined upwardly from the inner end of said extension as at 24 and engaged by the terminal portions 16 of the adjacent section 10 whereby said terminal sections and the adjacent intermediate section are interlocked to prevent relative longitudinal movement.

The terminal section 12 is U-shaped and of a height greater than the sections 10 to form a wheel guard 25. The inner sides of the arms of the sections 12 are cut away as at 26 and the inner ends of these cut away portions are inclined upwardly from the inner end of the section 12 and engaged with the terminal portions 18 of the extension 17 of the adjacent section 10 whereby the latter and the terminal section 12 are interlocked against relative longitudinal movement.

What is claimed is:—

1. In a sectional culvert, the combination of a plurality of tubular members arranged end to end, and extensions on the adjacent ends of said sections disposed in overlapping relation, the abutting sides of said extensions being correspondingly inclined to interlock the sections and secure the latter, against relative longitudinal movement.

2. In a sectional culvert, the combination of a plurality of intermediate sections arranged end to end, extensions on the adja-

cent ends of said sections disposed in overlapping relation and having their abutting sides correspondingly inclined to interlock the sections and secure same against relative longitudinal movement, and terminal sections detachably interlocked with respective limiting intermediate sections, said terminal sections having cross dimensions in excess of the cross dimensions of the intermediate sections.

3. In a sectional culvert the combination of a plurality of intermediate sections arranged with their longitudinal axes in alignment each of which is provided with extensions at its ends, said extensions being disposed respectively at the top and bottom of the sections and having their terminal portions correspondingly inclined, the terminal portions of one extension being engaged with the terminal portions of the op-

posite extension of the next intermediate section, a terminal section at one end of the culvert having an inwardly directed extension at its lower end provided with inclined terminal portions engaging with the inclined terminal portions of the extension of the adjacent intermediate section, and a terminal section at the other end of the culvert of substantially U-shape and having the inner sides of its arm cut away and the inner ends of the cut away portion inclined and engaged with respective terminal portions of the extension of the adjacent intermediate section.

In testimony whereof, I affix my signature, in the presence of two witnesses.

OWEN S. HALL.
